UNITED STATES PATENT OFFICE.

ELLA LOUISE SMITH, OF ROANOKE, ALABAMA.

BAND FOR INFANTS.

1,321,134.

Specification of Letters Patent. Patented Nov. 11, 1919.

Application filed September 17, 1918. Serial No. 254,392.

To all whom it may concern:

Be it known that I, ELLA LOUISE SMITH, a citizen of the United States, residing at Roanoke, in the county of Randolph and 5 State of Alabama, have invented certain new and useful Improvements in Bands for Infants, of which the following is a specification.

My invention relates to improvements in 10 bands for infants, and it consists in the combinations, constructions and arrangements herein described and claimed.

An object of my invention is to provide a 15 band for newly born infants which is easily applied and removed, and which does not require the use of pins or similar fastening means.

A further object of my invention is to 20 provide an infant's band which is curved to fit the body of the infant, and which is provided with means for preventing the band from slipping upwardly or downwardly.

A further object of my invention is to 25 provide a band of the type described which is readily adjustable to bodies of various sizes without impairing the means for preventing the slipping of the band.

Other objects and advantages will appear 30 in the following specification, and the novel features of the invention will be particularly pointed out in the appended claim.

My invention is illustrated in the accompanying drawings, forming part of this application, in which—

35 Figure 1 is a plan view of the band;

Fig. 2 is a detailed view showing a portion of the band provided with darts whose edges are designed to be sewed together to provide a rounded central portion;

40 Fig. 3 is a view showing the front of the band as applied to the body of an infant; and

Fig. 4 is a rear view of the band as applied to the infant's body.

45 In carrying out my invention I provide a body portion 1 of any suitable material, such as linen or flannel, of the shape shown in the drawings. At each end of the body portion are two V shaped extensions such as 50 those shown at 2 and 2' and 3 and 3' respectively. Sewed to the end of each extension is a tying string 4 which is preferably made of tape. Near the base of the extensions 2 and 2' is a slit 5 extending transversely of the major dimension of the band,

while a similar slit 6 is at the opposite end and on the opposite side of the central axis.

In making the band, the darts 7 are provided at the central portion thereof, as shown in Fig. 2, and the edges of these darts are sewed together, after which a reinforcing strip 8 of tape or other suitable material, is sewed along the central portion from one edge of the band to the opposite edge. The completed band, it will be observed, is bowed out so as to conform to the body of the infant.

In applying the band the central portion thereof is placed over the abdomen of the infant, as shown in Fig. 2, wrapped around the body, one of the extensions being passed through the slit 6 (see Fig. 3) and another extension 3' being passed through the slit 5. The ends of the extensions are then brought together and tied by means of the tying strings 4 in the manner shown in Fig. 2. It will be observed that these extensions, and their tying strings, are above the central portion of the infant's abdomen so as to prevent any injury thereto from rubbing or undue pressure.

A band constructed in accordance with my invention will neither slip up nor down, and thus obviates the chief objection to the ordinary infant's band. It is easily applied 85 or removed, and may be adjusted to fit bodies of various sizes.

I am aware that infants' bands have been made having extensions and slits, and I do not claim the same broadly. In the present 90 instance, however, the placing of the slits at opposite ends of the band, instead of in alinement at one end, provides space for slits of greater length, so as to give greater opportunity for adjustment thus enabling the 95 band to be drawn up to fit the bodies of very small infants, or to be let out to fit the bodies of larger infants. Furthermore, it does not weaken the band as much as where these slits are in alinement.

I am also aware that bands have been formed by cutting the upper and lower edges thereof on a curve to provide for the bowing out of the band. Such bowing, however, only prevents the band from slipping in one 105 direction, whereas the band formed according to my invention is bowed to conform to the body of the infant and this, taken in connection with the fact that the tying strings are fastened above and below the center of 110

the abdomen, prevents the slipping of the band either up or down, while at the same time forming a comfortable appliance, which obviates the use of pins or other retaining means.

I claim:

An infant's band comprising a body portion having parallel sides, provided with darts at the central portion thereof extending inwardly from the sides, the edges of the darts being sewed together to provide a central bowed out portion, a pair of V shaped extensions at the opposite ends of the body portion, a tying string secured to the end of

each extension, said body portion having 15 transverse slits of a length sufficient to receive the widest part of said V shaped extension, one of said slits being disposed on one side of the central longitudinal axis of the band near the base of one of said V 20 shaped extensions, and the other slit being disposed on the opposite side of the longitudinal axis of the band, and of the central transverse axis near the base of one of the V shaped extensions at the opposite end of the 25 band.

In testimony whereof I affix my signature.

ELLA LOUISE SMITH.
